METHOD FOR INITIATING IN SITU COMBUSTION WITH PYROPHORIC MATERIALS

Carl A. Cline and Louis David Trapnell, Ponca City, Okla., assignors to Continental Oil Company, Ponca City, Okla., a corporation of Delaware
No Drawing. Filed Oct. 20, 1960, Ser. No. 63,722
4 Claims. (Cl. 166—38)

This invention relates to a method for igniting subterranean hydrocarbon-bearing reservoirs in conducting recovery operations generally known as in situ combustion recovery. The in situ combustion of such reservoirs is a well known method for the secondary recovery of hydrocarbons, and this invention is particularly directed to the initiation of such subterranean combustion.

This technique of secondary production of hydrocarbons comprises the initiation of combustion in the carbonaceous strata of the reservoir and the resulting propagation of the combustion zone through the reservoir by either a direct or inverse oxygen-containing gas drive whereby the heat of combustion of a portion of the hydrocarbons displaces the remainder of the hydrocarbons in the reservoir to adjacent recovery wells.

A conventional method of in situ combustion recovery entails initiating combustion in the subterranean reservoir surrounding a well bore designated as the ignition well, whereafter the combustion front is directed toward surrounding recovery well bores traversing the reservoir. The combustion of the hydrocarbons in the reservoir reduces the viscosity of the other hydrocarbons therein, and the heated gas drive causes the hydrocarbons to be displaced to the recovery wells where they are produced in a conventional manner.

The initial step in conducting in situ combustion recovery is the initiation of combustion in the reservoir adjacent the ignition well. The basic mechanism of transferring the necessary heat required for continued combustion of a self-sustaining nature comprises injecting oxygen-containing gas through a heated portion of the reservoir adjacent the ignition well wherein combustion has been previously initiated. Various methods have been utilized to heat the reservoir to initiate combustion therein and to achieve the temperatures necessary for continuous self-sustaining combustion. These methods include utilizing downhole heaters of either an electrical or gas burner construction, injecting heated gases from the surface, injecting highly reactive chemicals such as halogens to react with the hydrocarbons of the formation, and injecting high energy fuels such as hydrazine along with strong oxidizing agents. The foregoing methods wherein a heating device is utilized require the insertion of a downhole heater into the well bore whereafter air is passed by the heater in order to elevate the temperature in the reservoir surrounding the ignition well. These heaters are complicated and expensive and the results are often other than satisfactory either due to the fact that the heat is not applied to the formation at the desired depth or the heat is undesirably concentrated at some particular location causing the heater or supporting cable to become subject to excess temperatures with a malfunction and loss of the heater prior to sufficiently initiating of combustion. The use of chemicals which produce heat by exothermic reaction with hydrocarbons has the inherent disadvantage of being subject to inadvertent reaction prematurely with the hydrocarbons present within the well bore at other than the desired location. The use of certain of the foregoing chemicals requires the inclusion of catalysts or inhibitors in order to control the rate of reactivity and heat produced therefrom in order to avoid the undesirable fusing

of rock or establishment of water blocks within the reservoir.

It is an object of the present invention to provide an improved method for initiating combustion in subterranean hydrocarbon-bearing reservoirs in order to establish in situ combustion therein.

Another object of the present invention is to provide an improved method of initiating in situ combustion whereby the application of heat to the reservoir is controlled both as to the amount and the location of application within the reservoir.

A further object of the present invention is to provide an improved method for initiating in situ combustion which is dependable, efficient and avoids the necessity of using complex equipment or ignition means within the well bore.

Other objects and advantages of the present invention will be apparent from the consideration of the following disclosure of invention.

In brief, the present invention is broadly directed to the initiation of in situ combustion by introducing a hydrocarbon-miscible pyrophoric substance into a subterranean reservoir followed by the injection of an oxygen-containing gas until the initiation of combustion is accomplished.

The initiation of in situ combustion in a subterranean reservoir containing hydrocarbons and being traversed by a plurality of well bores, one of which is an ignition well, as taught by the present invention is very simple and requires the utilization of substantially no downhole equipment. In general, any substantially hydrocarbon-soluble pyrophoric substances are suitable, with the preferred substances suitable for use in the present method being the oxidizable lower alkyl derivatives of boron, aluminum and zinc which are soluble in petroleum hydrocarbons. More specifically, the preferred substances include compounds having the following structures:

(R¹)₃B; R¹R²R³Al; R⁴R⁵Zn
in which R¹ is hydrogen or an alkyl group having from 1 to about 3 carbon atoms, R², R³, R⁴ and R⁵ are alkyl groups having from 1 to about 4 carbon atoms. Examples of suitable substances with their boiling points are listed below:

	B.P., ° C.
Trimethylborine	—21.8
Triethylborine	95
Triethylaluminum	207
Trimethylaluminum	126
Dimethylaluminum hydride	154
Dimethylzinc	46
Diethylzinc	118
Diisopropylzinc	136
Diisobutylzinc	170

Generally speaking, these substances produce in the neighborhood of 100,000 B.t.u. per gallon by combustion at atmospheric pressure, for example the heats of combustion of triethylaluminum and triethylborine are 127-700 B.t.u./gal. and 116,500 B.t.u./gal. respectively. As a consequence of the formation of combustion products of low specific heat, the effective combustion temperatures of these substances are also quite high.

In the operation of the method of the present invention, the pyrophoric substance is mixed with a suitable hydrocarbon, preferably one having a relatively low viscosity, such as kerosene, pale oil, or diesel fuel, in a container suitably adapted to preclude any contact with air or other oxygen-containing gas. The proportions of the solution are adaptable to individual formations in that one possible method of controlling the rate of heat production within the formation is to control the ratio

of pyrophoric substance to hydrocarbon. By the inclusion of a lesser amount of pyrophoric substance in the solution there is achieved a reduced concentration of the heat produced during the subsequent stage of initiating the in situ combustion, and the converse of the foregoing occurs when greater proportions of the pyrophoric substance are included in the solution. From the foregoing table it is evident that at least one of the suitable pyrophoric substances is a gas at normal conditions so it becomes possible to obtain homogeneous vapor phase mixture containing those substances, or they may be placed in a solution with liquid hydrocarbons after requisite conditions of pressure and temperature are met. The remaining pyrophoric substances are normally liquid and can be handled in solutions in hydrocarbons at atmospheric pressure by taking the normal precautions necessary with a highly combustible liquid.

Subsequent to the preparation of the fluid solution as specified above it is necessary that the solution be displaced into the subterranean reservoir surrounding the well bore of the ignition well. This step may be accomplished in any one of several methods which are conventional in the art. The mixture may be placed in the well bore adjacent to the subterranean reservoir by means of injecting it through a line in communication with the surface, or the solution may be placed in a suitable container and lowered into the well bore to a predetermined depth whereafter the solution is released from the container by a mechanical valve arrangement or by rupturing the container, providing it is of a sufficiently frangible nature. Prior to the placement of the pyrophoric solution in the well bore the bore should be evacuated of any oxygen-containing gas which may be accomplished in many ways, such as by merely injecting a volume of hydrocarbon into the well bore to form a blanket separating the solution from contact with the atmosphere or other oxygen-containing gases within the well bore.

Thereafter the pyrophoric fluid mixture is displaced into the reservoir adjacent the well bore by means of further injection of hydrocarbons, either gaseous or liquid, depending upon the nature of the pyrophoric mixture, so that pressure will be applied to the mixture causing it to be displaced into the formation. The placement of a specified amount of the pyrophoric fluid in the well bore is most readily accomplished by utilizing a container lowered into the well bore whereafter the specific volume is displaced in the reservoir to the desired distance. In the event that larger volumes of the pyrophoric solution are required to furnish the necessary heat, it is more advantageous to inject the solution through a surface line wherein greater volumes of the pyrophoric substance may be introduced, or the same volume in conjunction with greater amounts of hydrocarbons may be introduced. The displacement of the pyrophoric fluid into the reservoir may be controlled in order that the mixture may be placed at any predetermined distance from the ignition well bore, enabling the heat of combustion to be applied to the reservoir formation at the most desirable location.

The final step of the present invention is the injection of an oxygen-containing gas, such as air or elemental oxygen, into the reservoir wherein the pyrophoric substance has been previously displaced. Upon contacting the pyrophoric fluid the oxygen causes an immediate oxidation reaction to occur whereby peroxy compounds, carbon dioxide and minute quantities of water and metal oxides are formed, together with the release of great quantities of heat. Following the initial oxidation reaction, the rate of oxygen consumption and heat generation increase rapidly, probably promoted by the presence of the peroxy compounds, until the temperature within the formation has been raised to the combustion point of the hydrocarbons contained therein, usually in the range of 500 to 700° F. The method of the present invention is complete upon the production of sufficient heat by the

pyrophoric substance to establish self-perpetuating combustion of the hydrocarbons within the reservoir. Thereafter the secondary recovery method of in situ combustion may be carried forward by merely continuing the injection of an oxygen-containing gas, whereby the hydrocarbons of the formation provide the fuel to establish and propagate the combustion throughout the reservoir.

5 The pyrophoric substances disclosed herein as being operable may be utilized separately, or it is possible to 10 combine two or more of them into a mixture in order to take advantage of some of the individual characteristics of several, such as economics, availability, speed of reaction, etc. This method of initiating in situ combustion in the formation surrounding the well bore is particularly 15 applicable when preheating the formation prior to the injection of water or other displacement fluids. It is also utilizable as a means for providing heat in a well work-over situation, such as the removal of paraffin, or generally 20 in any instance where there is a need for heat stimulation.

The present method of heat generation may also be 25 utilized in conjunction with a fracturing operation, where- 30 in the pyrophoric substance is injected into the formation prior to fracturing, subsequent to the establishment of the fracture in the formation, or as the fracturing fluid to 35 which the hydraulic and hydrostatic pressure for accom- 40 plishing the pressure are actually applied. This will result in the substance being placed in the vertical or hori- 45 zontal fractures about a well bore and provide a more porous media wherein the combustion can be initiated. The utilization of a fracturing technique in conjunction 50 with initiating combustion as disclosed herein will be particularly advantageous when the porosity of the formation is limited due to the fact that there are often 55 combustion products formed which will plug a normally satisfactorily flowing reservoir. Certain other modifications in the foregoing disclosure of the invention will be apparent to those skilled in the art and the specific em- 60 bodiments disclosed are not to be construed as imposing limitations upon the scope of the present inventive method.

In order to disclose more clearly the nature of the 65 present invention, the following specific embodiments are 70 furnished to illustrate the herein described method. As an example, the method of the invention is applied to a subterranean reservoir containing crude oil of a viscosity of about 500 centipoises in a formation at a depth of 1015-1035 feet having a porosity of 25 percent and a 75 temperature of 105° F. Analysis of cores indicates combustion is developed at about 600° F., and that 33 B.t.u. of heat are required to raise the temperature of a cubic foot of the formation each degree Fahrenheit.

An injection of about 205 gallons of triethylaluminum into the 20 feet of formation is sufficient to provide 26 million B.t.u. of heat whereby the initiation of combus- 75 tion within the reservoir to the extent necessary to allow development of in situ combustion is accomplished.

The invention having been thus described, what is claimed and desired to be secured by Letters Patent is:

1. A method for initiating in situ combustion in a subterranean hydrocarbon-bearing reservoir traversed by a well bore which comprises introducing into said well bore a hydrocarbon-soluble substance selected from the class of compounds having the structures $(R^1)_3$, $R^1R^2R^3Al$, and R^4R^5Zn in which R^1 is hydrogen or an alkyl group having from 1 to about 3 carbon atoms, and R^2 , R^3 , R^4 and R^5 are alkyl groups having from 1 to about 4 carbon atoms, displacing said substance into said reservoir, and injecting an oxygen-containing gas through said well bore into said reservoir such that said substance can be im- 80 mediately contacted by subsequently injected oxygen-con- 85 taining gas to initiate oxidation and oxidizing said sub- 90 stance with oxygen-containing gas to produce heat suffi- 95 cient to ignite hydrocarbons present within said reservoir.

2. The method of claim 1 in which the hydrocarbon- 100 soluble substance is triethylborine.

3. The method of claim 1 in which the hydrocarbon-soluble substance is triethylaluminum.
4. The method of claim 1 in which the hydrocarbon-soluble substance is diethylzinc.
